UNITED STATES PATENT OFFICE

FRANK J. KENT, OF MONTCLAIR, NEW JERSEY, ASSIGNOR, BY MESNE ASSIGNMENTS, TO THE CLEVELAND TRUST COMPANY, OF CLEVELAND, OHIO, A CORPORATION OF OHIO

PISTON

Application filed June 27, 1927. Serial No. 201,650.

This invention relates to pistons and aims particularly to improve the construction of pistons formed of light weight metal.

One of the objects of the invention is to provide a piston in which the skirt may change shape due to temperature changes, without expanding diametrically to such an extent as to cause unsatisfactory operation of the piston in a cylinder, where, as is now common, the metal of which the cylinder is made has a smaller coefficient of expansion than the metal of which the piston is made.

Another object is to provide a piston so constructed, or having means incorporated therein in such manner, that all portions of the skirt may expand as fully and freely as though the skirt were not confined in the cylinder and yet without increasing the frictional drag between the thrust faces of the skirt and the cylinder during and after such expansion.

Another object is to provide a piston formed wholly or in the main of a material of a comparatively high coefficient of expansion, so constituted that skirt portions may expand fully and freely in a direction to increase the axial length of the piston solely or primarily.

Another object is to provide a piston including a head and a skirt, with the skirt so constructed and so inter-connected that, while the skirt is expandible and contractible in accordance with temperature conditions, the skirt will not change in girth on a rise of temperature.

Another object is to provide a piston including a head and a skirt, with the skirt so constructed and so connected to the head that, while the skirt is expandible and contractible in accordance with temperature conditions, the skirt will not change in girth on a rise of temperature.

Another object is to provide a piston including a head and a skirt, the skirt being expandible and contractible in accordance with temperature conditions, in combination with means for causing a contraction of the skirt when the temperature is raised.

Various other objects and advantages of

the invention than those hereinabove mentioned will be specifically pointed out or will be apparent hereinafter in the course of the below detailed description of the forms of the invention shown, in the accompanying drawings, as preferred ones of the various possible embodiments of the invention; it being understood, naturally, that such forms are merely illustrative of some of the many possible combinations and arrangements of parts well calculated to attain the objects of the invention, and hence said detailed description of such forms is not to be taken as at all defining or limiting the invention itself. That is to say, the scope of protection contemplated is of course to be taken from the appended claims, interpreted as broadly as is consistent with the prior art.

In the accompanying drawings:

Fig. 1 shows, partially in elevation, and partially in section, one form of the invention;

Fig. 2 is an axial section, taken on line 2—2 of Fig. 1;

Fig. 3 is a transverse section, taken on line 3—3 of Fig. 1;

Fig. 4 is an axial section, taken on line 4—4 of Fig. 2;

Fig. 5 is a plan view of a thermostatic element constituting a part of the form shown in Figs. 1 to 4;

Fig. 6 is an axial section, illustrating another form of the invention;

Fig. 7 is a view similar to Fig. 6, but taken on the line 7—7 of Fig. 6; and

Fig. 8 is a view similar to Fig. 4, but showing a modification of the form of the invention shown in Figs. 1 to 4.

Similar reference characters refer to similar parts throughout the several views of the drawings.

Referring to the drawings more specifically, in all of the illustrated embodiments, the piston, which is preferably formed of light weight material such as an aluminum alloy, comprises a head 10 and a skirt 11. The head is in the usual cylindrical form, having piers 12 which extend downwardly in

the conventional manner and which at their lower ends carry pin bosses 13.

The skirt, the upper part of which is insulated from the head in any desired manner, as by providing an air gap 14 extending around the greater part of the circumference of the piston, is in the form of a cylindrical spiral as the result of providing a spiral groove or grooves, in the present case a 10 single such groove, marked 15.

In all the illustrated embodiments also, the spiral skirt element is connected at its upper end with one of the piers 12; while the parts of such spiral element beyond and 15 below the last mentioned pier, define a tubular housing surrounding and spaced from the other pier and the two pin bosses. In order to insert the pin (not shown) this tubular housing, that is, the skirt, may have 20 cut-outs 16 opposite one of the bosses and defining a circle concentric with the pin receiving hole in the boss.

Referring now more particularly to the form of the invention shown in Figs. 1 to 5, 25 pairs of upper and lower lugs 17 are formed on the inside of the skirt, as shown in Figs. 2 and 3, and two oppositely disposed sets of such lug pairs are provided as shown in 30 Figs. 3 and 4. Spanning each upper and lower pair of lugs, at each side of the skirt, and mounted in the lugs as clearly shown in the drawings, is a thermostatic element 18. These elements are preferably bowed as 35 shown; and may be made up in the conventional way of a plurality of strips of metals of dissimilar coefficients of expansion. The thermostatic elements are so constructed that on raising the temperature thereof, they 40 tend to expand longitudinally, that is, to assume a curvature of greater radius. It will be clear that these thermostats may be so designed and incorporated that they will 45 function to elongate the spiral skirt as desired under predetermined operating temperatures; thereby to permit the skirt to maintain a constant diameter at different 50 temperatures and yet freely and fully expand in all portions on an increase in temperature; and, obviously, the arrangement 55 may be such that on the piston or any particular part of the piston reaching a certain predetermined temperature, the piston will even be contracted in girth.

Referring next to the form of the invention shown in Figs. 5 and 6, a thermostatic element 18^a is present, but here arranged generally horizontally, with its bowing, or convex face, downwardly directed. The thermostatic element 18^a is in the present 60 case like the similar element 18 of Fig. 1 in that it is of the bar type. The opposite ends of the element 18^a are set in diametrically opposite points in a mounting ring 19 nested in an annular recess within the head 65 10 located above an internal flange or ledge

10'. Bolted to the central point of the element 18^a, and depending therebelow, and arranged at right angles thereto, is a cross-bridge 20. Thrust rods 21 are secured at their upper ends in the opposite extremities 70 of the bridge. These rods diverge in a downward direction, and their lower ends are secured in lugs 17' on the inside of the lower end of the skirt 11. The thermostatic element 18^a, in the present case, is so constructed that on raising the temperature thereof, it tends to assume a curvature of smaller radius, that is, to exert a down push 75 on bridge 20. According to this construction, an undesirable rise in temperature of the skirt 11 will result in a downward thrust of rods 21, and thereby cause an axial enlargement of the spiral constituting the skirt; so that, according to the design of the parts, the skirt will be caused to maintain 80 a constant diameter at different temperatures or to have its girth contracted on any particular part of the piston reaching a certain predetermined temperature.

Comparing the forms of the invention 80 shown in Figs. 1 and 7, and which have just been described, it is pointed out that the prolongation thrust against the lower portion of the piston has in the case of the form of Fig. 7, its reaction point against 95 the head, and not against the upper portion of the skirt, as in the case of the form of Fig. 1; and by virtue of this distinction, the form of Fig. 7 is at present believed to represent a preferable construction over that 100 shown in Fig. 1.

However, referring to Fig. 8, it will be noted that the type of embodiment of Fig. 1, may also be carried out practicably to locate said reaction point in the head 10. 105 In Fig. 8, as in Fig. 1, a pair of thermostatic elements are employed. These elements of Fig. 8, marked 18', are precisely similar to the elements 18 of Fig. 1, except that the elements 18' are somewhat longer 110 and their upper ends are anchored in upper lugs 17', within the head 10.

Inasmuch as many changes could be made in the above constructions, and many apparently widely different embodiments of 115 the invention could be made without departing from the scope thereof, it is intended that all matter contained in the above description or shown in the accompanying drawings shall be interpreted as illustrative 120 and not in a limiting sense.

It is also to be understood that the language contained in the following claims is intended to cover all the generic and specific features of the invention herein described, 125 and all statements of the scope of the invention which, as a matter of language, might be said to fall therebetween.

I claim:

1. As a new article of manufacture, a 130

piston including a head, and a skirt having a spiral slot extending completely around the skirt and throughout the length thereof.

2. As a new article of manufacture, a piston including a head, and a skirt having a spiral slot extending throughout the length thereof and having a plurality of convolutions, the lower end of the slot opening into the lower edge of the skirt.

10 3. A piston having a head, a skirt element of spiral form joined at one end to the head, said element being flexible radially and axially and having a bearing face which conforms to a cylindrical surface, and thermally controlled means connecting the head and skirt element for exerting an axial thrust on said skirt element at a point spaced from the head to cause expansion of the skirt to manifest itself in an axial direction primarily.

20 4. A piston comprising a head, a skirt element joined at one end to the head and having its ends offset circumferentially, said element being flexible radially and axially 25 and having an exterior bearing face which conforms to a cylindrical surface, and means acting on portions of the skirt element spaced axially from the head for holding the skirt element against increase in girth 30 when expanded by heat.

35 5. A piston comprising a head, a skirt element joined at one end to the head and having its ends offset circumferentially, said element being flexible radially and axially and having an exterior bearing face which conforms to a cylindrical surface, and thermally controlled means connecting the head and skirt element for exerting an axial thrust on said skirt element at a point 40 spaced from the head to cause expansion of the skirt to manifest itself in an axial direction primarily.

In testimony whereof I affix my signature.

FRANK J. KENT.
